United States Patent Office

Des. 220,644
Patented May 4, 1971

220,644

MONEY BOX

Leva Delores Robinson, 2320 E. Harvard Ave.,
Fresno, Calif. 93705

Filed Nov. 19, 1969, Ser. No. 20,171

Term of patent 14 years

Int. Cl. D20—99

U.S. Cl. D52—4

FIG. 1.

FIG. 3.

FIG. 2.

FIG. 1.

FIG. 5.

FIG. 6.

FIG. 7.

FIG. 1 is a top plan view of a money box showing my new design;

FIG. 2 is an enlarged top plan view thereof with the top open;

FIG. 3 is a right side elevational view thereof with the top open;

FIG. 4 is a front elevational view thereof;

FIG. 5 is a left end elevational view thereof;

FIG. 6 is a rear elevational view thereof;

FIG. 7 is a bottom view thereof.

I claim:

The ornamental design for a money box, substantially as shown.
